EPPA H. RYON, OF WORCESTER, MASSACHUSETTS, ASSIGNOR TO CROMPTON & KNOWLES
LOOM WORKS, A CORPORATION OF MASSACHUSETTS.

WEFT-REPLENISHING LOOM.

933,492.

Specification of Letters Patent. Patented Sept. 7, 1909.

Application filed June 8, 1907. Serial No. 377,943.

To all whom it may concern:

Be it known that I, EPPA H. Ryon, a citizen of the United States, residing at Worcester, in the county of Worcester and 5 State of Massachusetts, have invented certain new and useful Improvements in Weft-Replenishing Looms, of which the following is a specification.

My invention relates to weft replenishing 10 looms, and particularly to that class of weft replenishing looms having a stationary magazine or hopper for bobbins or filling carriers at one end of the loom, and drop or change shuttle boxes at the other end of the loom, 15 the magazine having a plurality of compartments or guide-ways, preferably extending in a vertical plane, for sets of bobbins preferably of different color or character, corresponding to the number of shuttle boxes, one 20 set for each shuttle box, and also having a filling detecting mechanism to detect practical or substantial exhaustion of filling in the active shuttle, and to put into operation transferring mechanism to transfer a bob- 25 bin of the desired color or character from the magazine into the shuttle, to take the place of the practically exhausted bobbin, and also having selecting means, connected with and controlled by the movement of the 30 shifting shuttle boxes, to determine from which set of bobbins a bobbin shall be released from the magazine and transferred into the active shuttle.

In the class of looms above referred to, 35 the filling detecting mechanism has ordinarily been located on the drop or change shuttle box end of the loom, and provision made for the vertical movement of the shuttle boxes.

40 The object of my invention is to provide, in the class of looms referred to, a filling detecting mechanism, preferably a mechanical filling detecting mechanism, located at the magazine end of the loom, to detect practical or substantial exhaustion of 45 filling in the active shuttle when it is at the magazine end of the loom, and to permit of said shuttle being picked to the drop shuttle box end of the loom, and then returned to 50 the magazine end of the loom, and have a new bobbin transferred into said shuttle, if there is no change of shuttle boxes at the opposite end of the loom. In case there is a change of shuttle boxes at the opposite end

of the loom, then the transfer of the bobbin 55 from the magazine into the shuttle having the practically or substantially exhausted bobbin, is delayed until said shuttle becomes again the active shuttle and is picked to the magazine end of the loom, when said 60 transfer takes place.

In my improvements, the release of a bobbin from the magazine, to be transferred into the active shuttle, in case of the practical or substantial exhaustion of the bobbin 65 in said shuttle, is done in two operations. In case the filling detector indicates the practical exhaustion of the bobbin in the active shuttle, the supporting mechanism of the bobbins, in the compartment from which 70 the bobbin is to be released, is operated to allow the lowest of the set to drop down in the magazine, and be held in its dropped position above the discharging end of the magazine, until the shuttle, which caused the 75 indication of the dropping down of said bobbin, returns again to the magazine end of the loom, when the mechanism which supports said bobbin is again operated, allowing the bobbin to drop or move down to the dis- 80 charging end of the magazine and be transferred into the active shuttle.

By the construction of the bobbin holding and releasing mechanism above described, it is not necessary that the bobbin be immediately transferred into the active shuttle, after the indication of the practical exhaustion of the filling in said shuttle, so that after the active shuttle has been picked from the magazine end to the discharging end of 90 the loom there may be a change of the shuttle boxes, and a new shuttle brought into play, and this new shuttle may have the filling therein practically exhausted, and cause the operation of the filling detecting mechanism to indicate for a change of filling for said shuttle, and then said shuttle be returned to the other end of the loom, and another change of the shuttle boxes takes place, and the same operation may take place in 100 connection with the other two shuttle boxes, in case four shuttle boxes are used, so that every one of the four shuttles for the four shuttle boxes may have the filling therein practically exhausted, and cause the operation of the filling changing mechanism to indicate for a change of filling, but such change of filling 105 will not take place until the shuttle is again

picked to the magazine end of the loom, when the proper bobbin, corresponding to the bobbin in the shuttle, will be transferred. In connection with my improvements above referred to, I preferably use a thread cutter, and mechanism for operating the same, combined with the selecting and transferring mechanism, and operated by the selecting mechanism on the transfer of a bobbin from the magazine into the shuttle, to cut the filling thread on the bobbin discharged from the shuttle.

I have only shown in the drawings detached portions of a weft replenishing loom of the class referred to, and particularly the magazine end of the loom, with my improvements applied thereto, sufficient to enable those skilled in the art to understand the construction and operation thereof. I have shown in the drawings in this instance, my improvements combined with a magazine provided with means for holding the bobbins in the compartments thereof, and for releasing the bobbin; said holding and releasing means, connected with and operated by the movement of the drop or change shuttle boxes at the other end of the loom, are of substantially the same construction and operation as the means shown in the pending application for U. S. Letters Patent No. 298,939.

Referring to the drawings:—Figure 1 is a front view of a detached part of one end of a loom breast beam, and a part of a stationary magazine, and parts connected therewith, with my improvements combined therewith. Fig. 2 is a plan view of some of the parts shown in Fig. 1, looking in the direction of arrow *a*, same figure. The end of the lay, and part of a shuttle, not shown in Fig. 1, is shown in this figure, but the magazine and some parts connected therewith, shown in Fig. 1, are not shown in this figure. Fig. 3 is a section, on line 3, 3, Fig. 1, looking in the direction of arrow *b*, same figure, and also shows in section the lay, shuttle box and shuttle shown in Fig. 2. Fig. 4 shows parts of a filling detecting mechanism shown in Fig. 2, in a different position. Fig. 5 is an inner end view of the magazine, and the bobbin holding and selecting mechanism shown in Fig. 1, looking in the direction of arrow *c*, same figure. Fig. 6 is a section, on line 6, 6, Fig. 5, looking in the direction of arrow *d*, same figure. Fig. 7 is a section, on line 7, 7, Fig. 5, looking in the direction of arrow *e*, same figure. Fig. 8 corresponds to Fig. 1, with some parts left off, and showing the mechanism for operating the filling thread cutter, and, Fig. 9 shows the parts shown in Fig. 8 in a different position.

In the accompanying drawings, 1 is a detached portion of a loom side, 2 the breast beam, 3 the lay beam having a stationary shuttle box 4 on one end, for a shuttle 5

carrying a bobbin 6. On the end of the breast beam 2 is secured a stationary stand 7, which has secured thereto the inner end 8 of the magazine, which in this instance has four vertically extending compartments or guide-ways 8' for the heads of the bobbins 6, which are arranged in four sets or series, one set for each compartment, and drop down by gravity to the lower discharging end 8'' of the magazine. Each compartment or guideway 8' is provided at its lower end with mechanism for supporting the set of bobbins therein, and also for releasing the lowest bobbin in each set, preparatory to its passage to the discharging end 8'' of the magazine, to be transferred into the shuttle. In this instance said holding and releasing mechanism consists of a rocking lever or cradle 9, pivotally mounted at the lower part of the magazine. The transerrer arm 10 carries a transerrer 11, and has a downward extension 10' thereon, which carries a dagger 12, which is adapted to be moved in the path of the bunter 13 on the lay beam 3, in the usual way.

All of the above mentioned parts may be of the usual and well known construction, and particularly described in said application, Serial No. 298,939.

I will now describe my improvements, and first the filling detecting mechanism, which as above stated, is located on the magazine end of the loom, and is in this instance shown as a mechanical filling detecting mechanism.

On the end of the breast beam 2 is secured a stand 14, which has an inwardly extending arm 14', upon the inner end of which is a boss or hub 14'', forming a support for a longitudinally moving filling feeler or detector 15, which consists in this instance of a flattened blade, adapted to enter, through an opening in the shuttle, and engage the bobbin or filling therein, see Fig. 2. The feeler 15 has an elongated slot or opening 15' therein, through which extends a stud 16, carried on the arm 14' of the stand 14. The stud 16 acts to hold the feeler 15 in its proper position relative to the opening in the shuttle, and a washer 17 on said stud acts to hold the feeler 15 in its proper vertical position. The outer end of the feeler 15 is in this instance connected with a second blade 18, which is pivotally attached at its outer end to an extension 19' on a lever 19, which is pivotally mounted on a stud 20 on the stand 14, see Fig. 4. The lever 19 has its end beveled or pointed, as shown at 19''. The engagement of the filling on the bobbin 6 with the feeler 15, on the forward movement of the lay, as shown in Fig. 2, moves said feeler outwardly, and with it the arm 19' on the lever 19, causing the lever 19 to be moved inwardly. A helically coiled contraction spring 21, attached at one end to the arm 19' on the stand 14, and at its

other end to the arm 19' on the lever 19, acts to move inwardly the feeler 15 as the lay moves backwardly, and also to move outwardly the lever 19. A set screw 22 on the stand 14 on the breast beam 2 limits the outward movement of the lever 19.

On the inner end of the plate 14, secured on the upper side of the breast beam 2, at the end thereof, is a stud 23, on which is loosely mounted an angle lever 24, see Fig. 2. One arm of the angle lever 24 is made yoked shape, or has an open end slot 24' therein, to receive the end 25' on a rocking lever 25, see Fig. 1, having its hub 25" loosely mounted on a stud 26. The hub 25" has an extension 25''' thereon, see Fig. 4, carrying a pin 27, on which is pivotally mounted the upper end 28' of a rod or connector 28, see Fig. 1, to a cam lever, not shown, preferably operated by a cam, not shown, on the bottom shaft of the loom; not shown, to communicate a pivotal movement to said lever 24. The lever 24 has a movement communicated to it by the rocking lever 25 at every other pick of the loom. Said lever 24 has an elongated opening 24' in one arm thereof, to receive a stud 29 on one end of a link 30, the other end of the link 30 is pivotally attached to a stud 31 on an arm 32. The arm 32 has a stud 33 thereon, which extends into an elongated opening 14''' in the plate 14.

A helically coiled contraction spring 34 is attached at one end to the stud 23, and at its other end to the stud 33, and acts to move the arm 32 in the slot 14''' toward the lever 24, as shown in Fig. 2. The outer end of the arm 32 has a projection 32' thereon, which has a notch therein, which is adapted 40 to receive the pointed end 19'' on the lever 19, see Fig. 4.

When the feeler 15 is moved by engagement with the filling on the bobbin, on the forward beat of the lay, the engaging end 19'' of the lever 19 is moved inwardly as shown in Fig. 2, and out of the path of the extension 32'. The stud 33 on the arm 32 is drawn by the spring 34 to the inner end of the slot 14''' on the plate 14, see Fig. 2.

When the filling is exhausted from the bobbin, the feeler 15 is not moved backward on the forward beat of the lay, and consequently the lever 19 is not moved inwardly, but is left in its outward position to engage 55 the projection 32' on the arm 32, shown in Fig. 4, forming a fulcrum for said arm 32, so that the movement of the angle lever 24 in one direction, through the link 30, will move outwardly the inner end of the arm 32, and carry the stud 33 thereon to the outer end of the slot 14' in the plate 14, as shown in Fig. 4. The stud 33 has secured thereto one end of a curved shaped arm 35. The other end of said arm 35, see Fig. 1, is 60 connected with a pin 36 on one arm of an

angle lever 37, the hub 37' of which is pivotally mounted on a stud 38 on the loom side, see Fig. 6. The other arm of the angle lever 37 carries a stud 39, which is pivotally connected to the lower end of a link or connector 40. The upper end of the link or connector 40 is pivotally connected to a stud or pin 41 on the lever 42, which has its hub 42' loosely mounted on a rod 43, see Fig. 5, and is prevented from having longitudinal movement on said rod, by two lugs or bearings 7' on the stand 7, see Fig. 5. The rod 43 is loosely mounted to have a longitudinal and rocking movement in the bearings 7'' on the stand 7, see Fig. 5. A second longitudinally moving rod 44 extends parallel to the rod 43, in this instance above it, and is mounted to have a longitudinal and rocking movement in bearings 7''' on the stand 7, see Fig. 5. Said longitudinally moving rod 44, has the hub 45' on a lever 45, see Fig. 7, loosely mounted thereon, which lever carries a pin 46, to which is pivotally connected the upper end of a connector 47 to a cam lever, not shown, operated by a cam, not shown, preferably on the bottom shaft of the loom, not shown. The hub 45' is prevented from having a longitudinal movement on the rod 44 by the bearings 7''' on the stand 7, see Fig. 7.

The two longitudinally moving rods 43 and 44 are connected at one end by a plate 48, see Fig. 5, which in this instance is made bifurcated at each end, to receive a collar 49 fast on the rod 43, and a collar 50 fast on the rod 44. The plate 48 has upon its inner end two lugs or ears 48', see Fig. 7, between which extends a side extension 51' on one arm of an angle lever 51, the hub 51'' of which is loosely mounted on a stud 52 carried on the stand 7. The other arm of the angle lever 51 is adjustably connected, through a slot and bolt connection, with the lower end of a connector 53. The rod or connector 53 is connected, through intermediate connections not shown in this instance with the drop boxes, not shown, on the opposite end of the loom, so that the raising and lowering of said shuttle boxes, controlled by a pattern mechanism, not shown, will communicate, through the intermediate connections, and the connector 53 and angle lever 51, a reciprocating movement to both rods 43 and 44, to cause them to be moved longitudinally, according to the movement of the shuttle boxes, and in case of four shuttle boxes, to cause said rods to have four different positions longitudinally, corresponding to what is shown and described in said application, Serial No. 298,939, above referred to. The extreme outward position is shown by broken lines in Fig. 7.

Each rod 43 and 44 has fast thereon, to move longitudinally therewith, and to have a rocking motion therewith, a pair of operat-

ing fingers 54, and 55, respectively. On the lower pair of fingers 54 is a side extension 54' extending parallel to the rod 43. The side extension 54' extends loosely into a notch or recess in the lever 42, having its hub loosely mounted on the rod 43, and is adapted to have a reciprocating movement in said notch. The up and down movement of the lever 42 will communicate, through the extension 54', an up and down movement to the fingers 54. The two fingers 55 on the upper rod 44, also have a side extension 55' thereon, which extends parallel to the upper rod 44 and is adapted to extend into a notch or recess in the lever 45, to have a reciprocating movement in said notch or recess. The movement of the lever 45, through its connecting mechanism, will consequently communicate a rocking movement to the two fingers 55.

Arranged on the inner side of the inner end plate of the magazine, are four vertically moving bars 56, one for each compartment or guide-way of the magazine. These bars are loosely supported in guides or bearings 8'', see Fig. 6, to have an up and down movement. The lower end of each bar 56 has in this instance a swivel pin 9' attached thereto, which has an opening therethrough to loosely receive the end of a pin 9'', which is secured at its other end to the extension 9' on the rocking support 9, see Figs. 5, and 6. A helically coiled expansion spring 9^a encircles the pin 9'', and bears at one end against the swivel pin 9', and at its other end against the end of the extension 9'', on the support 9, and acts to yieldingly lock or hold said support 9 in its two positions.

The vertical movement of the bars 56 communicates to the rocking supports 9 a rocking movement, according to the vertical movement of said bars. On each bar 56 is a projection 56', adapted to extend in the path of the fingers 54 and 55, see Fig. 6. The upward movement of any one of the sliding bars 56, will cause the cradle or support 9 connected therewith, to have a partial rotation, allowing a bobbin to drop into the cradle, as shown by broken lines at the left in Fig. 3. On the upper forked end of each vertically sliding bar 56 is pivotally mounted a weighted latch 57, see Fig. 8, and when a bar 56 is in its raised position, the weighted end 57' of the latch 57 is free to move the latch into its raised position, shown in Fig. 8, and by broken lines in Fig. 1. In this position, the latch extends over a transverse bar 58, see Fig. 5, having its hub 58' fast on a rock shaft 59, loosely mounted in bearings on the stand 7, see Fig. 5. On the downward movement of a vertically moving bar 56, by the operation of one of the upper fingers 54, the support 9 is rocked or moved to release the bobbin, and allow it to drop to the discharging end of the magazine to be

transferred. And on the downward movement of a bar 56, the latch 57 will engage the bar 58 on the rock shaft 59. On said shaft 59 is fast the hub 60' of an arm 60 carrying a pin 60'' on which is mounted the hub 61' of a pin 61, which at its lower end extends through a hole in the head of a swivel pin 62 on the frame, see Fig. 3. A helically coiled expansion spring 62' encircles the pin 61, and acts to yieldingly hold the arm 60 and parts connected therewith in their two opposite positions, as shown in Figs. 8, and 9.

On the rock shaft 59 is fast a hub 63' of an arm 63, see Fig. 5, which carries a pin 64, which is connected through a connector 65, with one arm of an angle lever 6, pivoted on a stud 67, see Fig. 3. The other arm 66' of the angle lever 66, extends in the path of, and is adapted to engage an arm 12' on the dagger 12, to move said dagger and raise it into position to engage the bunter 13, to operate the transerrer arm 11 to transfer the dropped bobbin, in the usual way. The engagement of the bunter 13 with the dagger 12, returns the angle lever 66 into its opposite, normal position, and through the connector 65 moves the arm 63 and rocks the shaft 59, and moves the bar 58 into its normal raised position, shown in Fig. 6.

In connection with my improvements, I may use a thread cutting mechanism, connected with and operated by the transerrer mechanism, on the transfer of a bobbin, to cut the thread or filling on the bobbin transferred into the shuttle.

Figs. 8 and 9 of the drawings show a thread cutting device, which may be combined with my improvements and operated thereby. In this instance I provide the rock shaft 59 with an outwardly and downwardly extending arm 68, having pivotally attached to its outer end a downwardly extending bar 69, see Fig. 8, the lower end of which has a slot 69' therein into which extends a pin 70' on one arm of an angle lever 70, pivoted at 71 on a projection on the stand 7. The other end of the angle lever 70 is connected by a rod or connector 72 with the upper end of a lever 73, which is pivotally mounted on a stud 74 on the breast beam 2, and has the downwardly extending end 73', which is adapted to be brought into line with an actuating rod 75 of the thread cutting mechanism of the type shown in my pending application, Serial No. 368,781. A spring actuated pin 76 is adapted to enter into one of two openings or recesses 73'' in the lever 73, to hold it in its two positions, shown by full and dotted lines in Fig. 8.

When a bobbin is going to be transferred, as above described, the bar 58, as above stated, is moved downwardly. The downward movement of said bar will raise the arm 68 and the bar 69, and through the engagement of the pin 70' on the angle lever

70, with the lower end of the slot 69' in the bar 69, as the bar 69 is raised the angle lever 70 will be moved, and the cutting mechanism operated. The connector 47 for rocking 5 the fingers 55, has pivotally mounted thereon at 76°, the lower end of a hook lever 77, which has an engaging hook end 77', adapted to extend over and engage the pin 70', at pre-determined times and carrying a pin 77'', 10 which is adapted to engage an inclined or cam shaped surface 69'', on the inner lower edge of the bar 69, see Fig. 8. The raising of the bar 69, through the engagement of the inclined surface 69'' thereon with the pin 15 77'' on the hook lever 77, will move away said hook to disengage it from the pin 70' on the angle lever 70, as shown in Fig. 9. When the bar 69 is moved downwardly again, 20 through the movement of the bar 58 above described, the spring 78, attached at one end to the hook 77, and at its other end to the lower end of the connector 47, will act to move said hook inwardly at its hook end, to extend over the pin 70' on the angle lever 25 70, as shown in Fig. 8, and the downward movement of the connector 47 and the hook 77, will move down the plate 69, and through connections to the thread cutting mechanism, move the same to its inoperative position 30 shown by full lines in Fig. 8.

From the above description in connection with the drawings, the operation of my improvements in weft replenishing looms will be readily understood by those skilled in the 35 art, and is as follows:—

When a bobbin 6 in a shuttle 5 has a sufficient supply of filling thereon, the filling detector 15 will engage at its inner end with the filling in the shuttle, as the lay beats up, 40 as shown in Fig. 2, and will be moved backwardly, and will move the lever 19, so that the end 19'' thereof will not engage with the projection 32' on the arm 32, and the loom will continue to operate in the normal condition. 45

In case the filling on the bobbin in the active shuttle is practically or substantially exhausted, as shown in Fig. 4, then as the lay beats up, the filling feeler 15 is allowed to 50 enter the shuttle, actuated by the spring 21, such a distance that the lever 19 will be moved into a position to engage the stop 22, and the end 19'' into a position to be engaged by the projection 32' on the lever 32, and the lever 32, through the operation of the connector 28, the rocking lever 25, the angle lever 24, and the link 30, will be moved, from the position shown by full lines in Fig. 2, to the position shown in Fig. 4, against 60 the action of the spring 34, the engagement of the projection 32' with the end 19'' of the lever 19, serving as a fulcrum for the outer end of said lever.

The movement of the lever 32, from the 65 position shown by full lines in Fig. 2 to the

position shown in Fig. 4, will, through arm 35 move the angle lever 37, and the connector 40 to the lever 42 fast on the shaft 43, and rock said shaft, and with it the fingers 54 fast thereon, said fingers forming a part of 70 the selecting mechanism for the bobbins, and the movement thereof, to bring one of said fingers into a position in line with the compartment from which a bobbin is to be selected, being controlled by the longitudinal 75 movement of the rod 43, through connections to the shuttle boxes, and by the movement of said boxes, as fully described in application, Serial No. 298,939, above referred to.

The movement of a finger 54 in line with 80 one of the compartments of the magazine, as shown in Fig. 6, will cause said finger to engage the projection 56' on a vertically movable bar 56, connected at its lower end, through a swivel pin 9' with the extension 85 9'' on the rocking support 9, and raise said bar 56, from the position shown by full lines in Fig. 6 to the position shown by broken lines, and through connections to the rocking support 9, move said support, from the 90 position shown by full lines in Fig. 3 to the position shown by broken lines in said figure, to allow the lowest bobbin in the compartment to move down the distance of one bobbin, and be held there, as shown in said 95 Fig. 3.

The helically coiled spring 9''' on the pin 9' acts to yieldingly hold and retain the rocking support 9 in this position. The upward movement of the bar 56 allows the 100 weighted end 57' of the latch 57, pivotally mounted at the upper forked end of said bar, to move the latch outwardly, over the transverse bar 58, as shown by broken lines in Fig. 6, and full lines in Fig. 8. 105

During the operation of the mechanism above referred to, the shuttle with the substantially or practically exhausted filling, is picked to the other end of the loom. If there is no change of shuttle boxes at said 110 end of the loom on this pick, then the same shuttle is returned to the magazine end of the loom, and the selecting mechanism for the bobbins remaining in the same position, the upper finger 55, through the movement 115 of the connector 47 by a cam lever and cam, not shown, will move downwardly a bar 56, by engaging the projection 56' thereon, from the position shown by dotted lines in Fig. 6, to the position shown by full lines in Fig. 6. 120 The downward movement of a bar 56 will, through connections to the rocking support 9, move said support, from the position shown by broken lines in Fig. 3, to the position shown by full lines, releasing the bobbin 6 shown by broken lines, and allowing it to drop down to the lower discharging end of the magazine, preparatory to being transferred into the shuttle, by the movement of the transerrer 11 on the transerrer arm 10. 130

The downward movement of the slide 56 causes the latch 57 to engage with the transverse bar 58 and move downwardly said transverse bar and rock the shaft 59, against the action of the spring 62". The rocking of the shaft 59, through arm 63 fast on said shaft, connector 65, and the angle lever 66 engaging with its arm 66' the arm 12' on the dagger 12, moves up said dagger, from the 10 position shown in Fig. 3 into a position in the path of and to be engaged by the bunter 13 on the forward movement of the lay, to cause through the movement of said dagger 12, pivotally mounted on the arm 10' of 15 the transerrer arm 10, a downward movement of the transerrer 11, to transfer a bobbin into the active shuttle.

If there is a change in the shuttle boxes at the opposite end of the loom, after the 20 shuttle with the practically or substantially exhausted filling enters its box on that end of the loom, then through the change of shuttle boxes, and the connections to the longitudinally moving rods 43 and 44, the position of the fingers 54 and 55 is changed, to bring said fingers in alinement with the compartment having bobbins of a color or character corresponding to the bobbin in the shuttle thrown across the lay to the magazine end. If the bobbin in said shuttle has 25 a sufficient supply of filling thereon, then on the forward beat of the lay, the engagement of the filling with the feeler 15 will move the lever 19 into the position shown in 30 Fig. 2, and the loom will continue to operate in the normal way, leaving the bobbin shown by broken lines in Fig. 3, supported in the position shown by the rocking support 9, and yieldingly held there by the spring 9".

This operation will be repeated for four 35 changes of the shuttle boxes in case the shuttle boxes are changed every time that a shuttle having a bobbin with the filling thereon practically exhausted, enters its box on the 40 end of the loom opposite the magazine, but when the shuttle having the bobbin therein which was first practically exhausted, comes in line with the race-way and is thrown to the magazine end of the loom, then on the 45 forward beat of the lay, the filling feeler 15 will enter the shuttle, as shown in Fig. 4, and through intermediate connections operate the rocking support 9, to move it from the position shown by broken lines in Fig. 3 50 to the position shown by full lines in said figure, to release the bobbin shown by broken lines, and allow it to drop to the lower discharging end of the magazine, to be transferred into the shuttle in the manner above 55 described.

It will thus be seen that by means of my improvements, the rocking support 9 for each compartment has two positive movements, one to allow a bobbin to move toward

the discharging end of the magazine and be 65 retained there, and the other to allow the bobbin to move to the discharging end of the magazine. If there is a change of the shuttle boxes at the opposite end of the loom 70 between these two movements of the rocking support, then the second movement of the rocking support is held up and does not take place until the shuttle, having a bobbin with filling of a color or character thereon corresponding to the bobbin moved down and 75 held by the rocking support, is again picked to the magazine end of the loom.

The operation of the thread cutting mechanism will be readily understood from the 80 above description in connection with the drawings: On the operation of the mechanism above described, to transfer a bobbin from the magazine into a shuttle, the rocking of the shaft 59 will raise the arm 68 and the bar 69, through the engagement of 85 the pin 70' with the lower end of the slot 69' in the bar 69, will rock the angle lever 70, and through connector 72 will move the lever 73, from the position shown by full 90 lines to the position shown by broken lines in Fig. 8, and into the path of the rod 75, to cause the operation of the thread cutting mechanism, as fully described in my pending application, Serial No. 368,781, above referred to. The raising of the bar 69 causes 95 the inclined surface 69" thereon to engage the pin 77" on the hook arm 77, and move the hook arm 77 away from the pin 70', as shown in Fig. 9. When the bar 69 moves down to its lowered position, the pin 77" 100 will ride up on the inclined edge on said bar and the spring 78 will act to move the hook end 77' of the hook lever 77 over the pin 70', as shown in Fig. 8. The raising of the connector 47 to move down the finger 55, from the position shown in Fig. 8 to the position shown in Fig. 9, will cause the hook lever 77, 105 pivotally mounted on the connector 47, to move up with said connector 47, and the spring 78 will act to move the hook end 77' of the lever 77 over the pin 70' on the angle lever 70, and the downward movement of the connector 47, from the position shown in Fig. 9 to the position shown in Fig. 8 will 110 move the angle lever 70 and the connector 72, to move the arm 73, from the position shown by broken lines to the position shown by full lines. The connector 47 carrying the hook lever 77 has a vertical movement at 115 predetermined intervals, preferably every 120 other pick.

It will be understood that the details of construction of my improvements may be varied if desired, and they may be adapted to be applied to weft replenishing looms of 125 different construction and operation, having a stationary magazine with a plurality of compartments for bobbins or filling carriers.

Having thus described my invention, what I claim as new and desire to secure by Letters Patent is:

1. In a weft replenishing loom, a magazine for bobbins, having a plurality of compartments, a bobbin support for each compartment, a filling detector to detect the near approach of exhaustion of filling in a shuttle, connections between said filling detector and said bobbin support, to move said support and allow a bobbin to move toward the transerrer of the transerrer mechanism, and said transerrer, a separate connection to said support, to give said support a second movement, to allow the bobbin to move into a position to be transferred into a shuttle.
2. In a weft replenishing loom, a magazine for bobbins having a plurality of compartments, a bobbin support for each compartment, adapted to be moved in two directions, a filling detector to detect practical exhaustion of filling in a shuttle, connections under control of said filling detector to move said support in one direction on the practical exhaustion of filling in an active shuttle, separate connections to move said support in the other direction, to allow a bobbin to move into a position to be transferred into a shuttle.
3. In a weft replenishing loom, a magazine for bobbins, having a plurality of compartments, a rocking support for the bobbin in each compartment, means to rock any one of the said supports in one direction, and separate means to rock said support in an opposite direction, combined with means for holding said rocking support in either position.
4. In a weft replenishing loom, a magazine for bobbins, having a plurality of compartments, a filling detector adjacent thereto, a bobbin support for each compartment, connections between said filling detector and said supports, to cause any one of the said supports to be moved in one direction, on the practical exhaustion of filling in an active shuttle, and separate means to move said bobbin support in the opposite direction.
5. In a weft replenishing loom, a magazine for bobbins, having a plurality of compartments, a bobbin support for each compartment, adapted to be moved in two directions, a filling detector, connections from said bobbin support to said filling detector, to move said support in one direction, and separate connections, controlled by a pattern mechanism, to move said support in the other direction, to allow a bobbin to move into a position to be transferred into a shuttle.
6. In a weft replenishing loom, a stationary magazine, having a plurality of compartments for bobbins, and supports for said bobbins, a filling detector, means con-

trolled by said filling detector to move said supports in one direction, a dagger arranged to be operated by a bunter on the lay, and said bunter and lay, combined with connections from said bobbin supports to said dagger, to cause the said dagger to be moved into the path of the said bunter when any one of the bobbin supports are moved to release a bobbin therefrom.

7. In a weft replenishing loom, having a stationary magazine with a plurality of compartments, the combination with a transerrer mechanism, of devices for ejecting a bobbin from any compartment, a support for said ejected bobbin under the transerrer mechanism, of mechanism for operating the filling thread cutting mechanism when said transferring mechanism is operated, on the transfer of said ejected bobbin from the magazine into a shuttle, to sever the thread of the ejected bobbin.

8. In a weft replenishing loom having a stationary magazine with a plurality of compartments, the combination with the transferring mechanism, of devices for ejecting a bobbin from any compartment, a support for said ejected bobbin under the transferring mechanism, of mechanism for operating the filling thread cutting mechanism when said transferring mechanism is operated, on the transfer of said ejected bobbin from the magazine into a shuttle, to sever the thread of the ejected bobbin, and on one pick thereafter to sever the thread of the transferred bobbin.

9. In a magazine for a weft replenishing loom, a plurality of compartments, and a bobbin support for each compartment, a sliding bar connected to each support, rods having a sliding and oscillating motion, means, under the control of a pattern mechanism, for sliding said rods, connections from one of said rods to a filling detector, and said detector, connections from the other rod to a rotatable cam, and said cam, a device on one of said rods for operating the said sliding bars in one direction, and a device on the other rod for operating said sliding bars in the opposite direction.

10. In a magazine for a weft replenishing loom, a rocking bobbin support for each compartment, a sliding bar connected to each support, and a spring lock between each of the said supports and one of the sliding bars.

11. In a magazine for a weft replenishing loom, having a plurality of bobbin compartments, a rocking support for each of said compartments, a sliding bar connected to each support, said sliding bars having latches fulcrumed thereon, a transfer mechanism, a latch connected therewith, a bunter on the lay, and a device connected with the last named latch, and adapted to be operated by any one of the latches on said sliding bar,

when the said sliding bar is moved in one direction.

12. A magazine for a weft replenishing loom, having a plurality of compartments, a bobbin support for each compartment, a sliding bar connected to each support, a rod having a sliding and an oscillating motion, a finger on said rod to operate said sliding bars in one direction, a second rod having a sliding and oscillating motion, with a finger on said second rod to operate the sliding bars in the opposite direction, combined with means for retaining said sliding bars in either position.

15. 13. In a weft replenishing loom, a magazine having a plurality of bobbin compartments, a bobbin support for each compartment, two rods, and means, under the control of a pattern mechanism, to give said rods a lateral motion, a filling detector, connections from said filling detector to one of said rods, and connections from the other rod to a rotatable cam, and said cam.

14. In a weft replenishing loom, drop boxes, means for operating the same, a magazine having a plurality of compartments, a bobbin support for each compartment, two rods having fingers thereon, and adapted to coöperate with the bobbin supports, devices under the control of a pattern mechanism, to give said rods a lateral motion in unison with the boxes, a filling detector, connections from said detector to one of said rods, to oscillate said rod, and connections from the second rod to a rotatable cam, and said cam, to oscillate the second rod.

15. In a weft replenishing loom, a magazine for bobbins having a plurality of compartments, supports for said bobbins, a filling detector on the magazine end of the loom to detect the practical exhaustion of the filling in an active shuttle, when the said shuttle is at the magazine end of the loom, means connected with said detector, to indicate for a change of bobbins in the active shuttle on the practical exhaustion of the filling thereon, and separate means to cause a change of filling when the said shuttle is again picked to the magazine end of the loom.

16. In a weft replenishing loom, a maga-

zine containing a plurality of bobbin compartments, a lay, a filling detector at the magazine end of the loom, a plurality of devices under control of said filling detector, 55 said devices corresponding in number to the bobbin compartments, to give a primary indication on the practical exhaustion of the filling in a shuttle at the magazine end of the loom, combined with devices under control of pattern mechanism, to cause a fresh supply of filling, corresponding to that in the active shuttle, to move into position, to be transferred into said shuttle, when it is again picked to the magazine end of the 65 loom.

17. In a weft replenishing loom, a stationary magazine having a plurality of compartments for cops or bobbins, a lay, a filling detector at the magazine end of the loom, a plurality of devices, corresponding in number to the magazine compartments, connected with the said detector, to cause a primary indication to be made, through the filling detector, when a filling in any shuttle at the magazine end of the loom has been exhausted to a pre-determined amount, combined with means to automatically transfer a bobbin or cop from a compartment corresponding to the active shuttle into said shuttle, when it is again picked to the magazine end of the loom.

18. In a weft replenishing loom, a magazine for bobbins or cops having a plurality of compartments, a lay, a support for the bobbins or cops in each of the said compartments, a filling detector at the magazine end of the loom, devices connected with said supports and under control of said detector, to cause a primary indication, and allow a bobbin or cop having filling thereon corresponding to that in the active shuttle, to move toward a position to be transferred, combined with devices under control of pattern mechanism to cause said bobbin or cop to be transferred into the shuttle, when said shuttle is again picked to the magazine end of the loom.
